6 Claims. (Cl. 209—36)

In cereal mills which are provided with pneumatic systems for conveying and elevating grain and mill products, the separation from whole grain of impurities which have been removed therefrom by air currents during elevation is frequently effected at the upper termination of an elevating pipe in special separators, such as that described in British patent specification No. 684,169, wherein the elevated materials are separated from the elevating air of which at least a part is redirected to pass through a single comparatively thin falling curtain of the separated materials so as to remove the said impurities by aspiration. While such special separators are suitable in circumstances where the volume of elevating air is large and the quantity of material elevated is comparatively small they are at a considerable disadvantage when considered in relation to a high capacity, low air volume pneumatic conveying system in that, because even if the whole of the elevating air is redirected for the purpose, the total volume of air available for aspiration is sufficient only to provide aspirating velocities in channels of comparatively small cross-section. The effect of the free admission to such a channel of the comparatively large quantity of material elevated would be to create a material curtain layer of such considerable thickness that complete aspiration would be impossible in the space available. Furthermore, with such a thick curtain layer of material traversing an aspirating channel, variations in the relative quantities of air and material could cause fluidisation of at least part of the curtain layer in which event the stream of material would become uncontrollable and might completely fill the channel and stop the aspirating process, or might cause good material to be carried over into the impurities disposal equipment.

An object of the present invention is to provide an improved pneumatic elevating system in which the above disadvantage is obviated.

According to the invention, the system comprises a main elevating pipe which discharges into an air separator, the separated elevated material being collected in a collecting chamber from which it is transferred to a regulating hopper provided with a plurality of narrow, preferably adjustable, slots, through which the elevated material discharges in a plurality of relatively thin curtain layers in an aspirating channel along which a controllable quantity of separated elevating air is directed so as to pass successively through each curtain layer. With such an improved arrangement, effective aspiration is provided while the slots trap and retain within the hopper any large impurities which might damage the separator outlet feeder.

Referring to the accompanying drawings:

Figures 1 and 2 are side and cross-sectional views respectively of an elevating system in accordance with the invention, and

Figure 3 is a section on B—B of Figure 2, a secondary separator also being indicated.

In the embodiment shown the upper termination of a main elevating pipe 1 of circular cross-section is con-

2

nected to a separator 2 of substantially rectangular cross-section by a transition element 3 of constant cross-sectional area arranged to spread the elevated materials over the whole width of the separator 2. Immediately above the transition element 3 a branch air-duct 4 is provided whereat the elevating air is separated from the stream of elevated material allowing the latter to continue to move under its own impetus along a path bounded by a deflector surface 5 which in conjunction with a suitable "material-cushion" check-box 6 re-directs it into a collecting chamber 7, a portion of the base of which takes the form of a counterbalanced hinged trap valve 8 adjustably arranged to permit the free passage of all material in excess of that quantity required to form a sealing layer of sufficient thickness to prevent the passage of air therethrough. Immediately below the collecting chamber 7 and having its walls continuous with the walls thereof, is a regulating hopper 9, one wall 10 of which forms part of the boundary of a downward extension 11 of the branch air-duct while the opposite wall 12, which is inclined inwardly towards the bottom and is provided with a plurality of adjustable slots 13 each of which extends horizontally over the full width of the hopper 9, forms part of the boundary of an aspirating channel 14 into which air from the extension 11 of the branch air-duct is directed. At a position below the regulating hopper 9, the aspirating channel 14 and the downward extension 11 of the branch air duct conjoin to provide a Y-junction 15, a lower extension of which forms the outlet duct for aspirated material and communicates with a rotary or similar outlet valve-feeder 16.

The cross-sectional area of the aspirating channel 14 may be from 2 to 2½ times that of the main elevating pipe 1, and its walls are parallel so that the wall 17 opposite the inwardly inclined and slotted wall of the regulating hopper is also inclined and provides a receiving surface down which aspirated material may be guided to the outlet valve-feeder 16. Above the top exit slot of the regulating hopper 9 the narrow side walls of the aspirating channel 14 converge to make a junction with a horizontal bye-pass air-duct 18, which passing along the outside of the collecting chamber connects the branch air-duct 4 with an outlet air-duct 19 leading to a secondary air separator 20, preferably of the cyclone type. At the junction of the aspirating channel 14 and the bye-pass air-duct 18, an adjustably hinged proportioning air-valve 21 is provided whereby the relative quantities of separated elevating air flowing from branch air-duct 4 through the aspirating duct 14 and the bye-pass duct 18 respectively to outlet air-duct 19 can be regulated so that only that proportion of the total separated air in branch air-duct 4 which is necessary for a specific aspirating requirement is caused to flow through the aspirating duct 14, the unwanted proportion of the separated air being caused to flow along the bye-pass air-duct 18 to outlet air-duct 19 thus bye-passing the aspirating channel, the said adjustably hinged proportioning air-valve being manually controllable by means of an external adjustment knob 30 mounted on an extension of the air-valve spindle 31 which passes through the wall of the duct to the outside of the apparatus in order to provide that the relative proportions of separated air flowing along the alternative paths available can be adjusted to an optimum while the apparatus is in operation.

Material which enters the collecting chamber 7 after having been separated from the conveying air, forms on the base of the chamber a layer, part of which rests on the counter-balanced hinged trap valve 8. When this layer is of such depth and density as to prevent any substantial flow of air from the collecting chamber through the valve 8, the weight of the material supported on the valve 8 causes it to open by an amount which will permit

the passage therethrough of a quantity of material equal to the amount being continuously received in the collecting chamber 7. From the collecting chamber 7 the material falls by gravity into the regulating hopper 9 wherein a substantially constant level of material is maintained by adjustment of the slot-openings 13 leading therefrom the said adjustment applying simultaneously to the effective depths of all the slots, and being regulated in accordance with movements of a manually operable adjustment knob 32 situated on the outside of one of the lateral boundary walls of the apparatus, and carried on a horizontally extending shaft 33, which supports two pinions 34 engaging racks 36 carried at each side of a slotted slideplate 35. Rotation of knob 32 raises or lowers the plate 35 and so enables the setting of the optimum slot depth to be effected while the apparatus is in operation. The material passes into the aspirating channel 14 through all slots 13 below the top level of the material, at a velocity subject to the pressure-head and the angle of slip of material, and tends to attain a vertical path under the influence of gravity, but, due to the lifting tendencies of the aspirating air flowing upwards in the aspirating channel 14 will be deflected so that heavier material elements will move towards and down the remote side 17 of the aspirating channel while the lighter material elements will be entrained in the air and transported via the outlet air-duct 19 to the secondary air separator 20, the quantities of the separated elevating air which are caused to pass up the aspirating channel and through the bye-pass duct 18 thereof being relatively controlled by the adjustable proportioning air valve associated therewith.

The aspirating channel wall 17 which is parallel with the slotted wall is provided with a covered opening 22 to permit of access to the slots 13; observations windows 23 are provided in the narrow walls of the aspirating channel 14 to facilitate slot and air quantity adjustment, and a service door 24 is provided in the side wall of the regulating hopper 9 to give cleaning access for removing trapped materials.

By providing that the material to be aspirated is passed into the aspirating channel 14 through narrow slots 13, it is ensured that large unwanted material which could damage the outlet feeder-valve 16 is prevented from entering the aspirating channel 14 and also that the material which passes through the slots 13 traverses the aspirating channel 14 in a plurality of thin curtain-layers through which the separated elevating air can pass freely to effect adequate aspiration for the removal of impurities. By enabling the relative quantities of air passing along the aspirating channel 14 or the alternative bye-pass channel 18 to be adjusted by the proportioning-valve means 21 it is ensured that sensitive control of the intensity of aspiration may be achieved. Since the aspirating channel 14 is arranged to slope the aspirated material passes down one wall of the channel and thus offers the minimum interference with the aspirating process.

What I claim is:

1. An air separation device for use in pneumatic elevating systems, comprising an air separator, a main elevating pipe discharging into said air separator, a collecting chamber in which separated elevated material from said separator is collected, a regulating hopper into which said separated elevated material is transferred from said collecting chamber, said regulating hopper having a plurality of narrow adjustable slots, an aspirating channel running past and in communication with said slots so that said separated elevated material discharges in a plurality of relatively thin curtain layers into said aspirating channel, and duct means for conveying a controlled quantity of separated elevating air from said separator to said aspirating channel enabling said separated elevating air to pass successively through each said curtain layer.

2. An air separation device for use in pneumatic elevating systems, comprising an air separator, a main

5 elevating pipe discharging into said air separator, a collecting chamber in which separated elevated material from said separator is collected, a regulating hopper into which said separated elevated material is transferred from said collecting chamber, said regulating hopper being tapered and having an inwardly inclined wall having a plurality of narrow adjustable slots therein, an aspirating channel having parallel walls, one of which is common with said slotted wall, said separated elevated material discharging through said slots in a plurality of relatively thin curtain layers into said aspirating channel, duct means for conveying a controlled quantity of separated elevating air from said separator to said aspirating channel enabling said separated elevating air to pass successively through each said curtain layer, and an outlet valve feeder means below said aspirating channel, the wall of said aspirating channel opposite said common slotted wall acting as a receiving surface down which said material which has not been removed by aspiration may be guided to said outlet valve feeder.

10 3. An air separation device for use in pneumatic elevating systems, comprising an air separator, a main elevating pipe discharging into said air separator, a collecting chamber in which separated elevated material from said separator is collected, a regulating hopper into which said separated elevated material is transferred from said collecting chamber, said regulating hopper having a plurality of narrow adjustable slots, an aspirating channel running past and in communication with said slots so that said separated elevated material discharges in a plurality of relatively thin curtain layers into said aspirating channel, duct means for conveying a controlled quantity of separated elevating air from said separator to said aspirating channel enabling said separated elevating air to pass successively through each said curtain layer, bye-pass means which bye-passes said aspirating channel, and an adjustable air valve associated with said bye-pass means, said air valve controlling the relative proportions of the separated elevating air passing through said aspirating channel and said bye-pass means.

15 4. An air separation device for use in pneumatic elevating systems, comprising an air separator, a main elevating pipe discharging into said air separator, a collecting chamber in which separated elevated material from said separator is collected, a regulating hopper into which said separated elevated material is transferred from said collecting chamber, said regulating hopper being tapered and having an inwardly inclined wall having a plurality of narrow adjustable slots therein, an aspirating channel having parallel walls, one of which is common with said slotted wall, said separated elevated material discharging through said slots in a plurality of relatively thin curtain layers into said aspirating channel, duct means for conveying a controlled quantity of separated elevating air from said separator to said aspirating channel enabling said separated elevating air to pass successively through each said curtain layer, an outlet valve feeder means below said aspirating channel, the wall of said aspirating channel opposite said common slotted wall acting as a receiving surface down which said material which has not been removed by aspiration may be guided to said outlet valve feeder, and being provided with a covered opening to permit access to said slots, bye-pass means which bye-passes said aspirating channel, and an adjustable air valve associated with said bye-pass means, said air valve controlling the relative proportions of the separated elevating air passing through said aspirating channel and said bye-pass means, observation windows being provided in said aspirating channel in the walls adjacent the slotted wall to facilitate slot and air control adjustment.

20 5. An air separation device for use in pneumatic elevating systems comprising an air separator, a main elevating pipe discharging into said air separator, a collecting chamber in which separated elevated material from said separator is collected, a regulating hopper into which

said separated elevated material is transferred from said collecting chamber, said regulating hopper being tapered and having an inwardly inclined wall having a plurality of narrow adjustable slots therein, an aspirating channel having parallel walls, one of which is common with said slotted wall, said separated elevated material discharging through said slots in a plurality of relatively thin curtain layers into said aspirating channel, duct means for conveying a controlled quantity of separated elevating air from said separator to said aspirating channel enabling said separated elevating air to pass successively through each said curtain layer, an outlet valve feeder means below said aspirating channel, the wall of said aspirating channel opposite said common slotted wall acting as a receiving surface down which said material which has not been removed by aspiration may be guided to said outlet valve feeder, and being provided with a covered opening to permit access to said slots, bye-pass means which bye-passes said aspirating channel, and an adjustable air valve associated with said bye-pass means, 20 said air valve controlling the relative proportions of the separated elevating air passing through said aspirating channel and said bye-pass means, observation windows being provided in said aspirating channel in the walls adjacent the slotted wall to facilitate slot and air control adjustment, and a service door being provided in the side wall of the said regulating hopper to give cleaning access for removing materials trapped by said slots.

6. An air separation device for use in pneumatic elevating systems, comprising an air separator, a main elevating pipe discharging into said air separator, a collect-

ing chamber in which separated elevated material from said separator is collected, a regulating hopper, a counter-balanced hinged trap valve in the bottom of said collecting chamber adjustably arranged to permit the passage 5 to said regulating hopper of separated elevated material in excess of that quantity required to form a sealing layer of sufficient thickness to prevent the passage of air therethrough, said regulating hopper having a plurality of narrow adjustable slots, an aspirating channel 10 running past and in communication with said slots so that said separated elevated material discharges in a plurality of relatively thin curtain layers into said aspirating channel, and duct means for conveying a controlled quantity of separated elevating air from said separator to said aspirating channel enabling said separated elevating air to pass successively through each said curtain layer.
